INVENTOR,

DANIEL H. STRAYER

By Martin O. Smith, Atty.

UNITED STATES PATENT OFFICE

DANIEL H. STRAYER, OF VENICE, CALIFORNIA

WATERPROOF RECEPTACLE

Refiled for abandoned application Serial No. 279,372, filed May 21, 1928. This application filed April 11, 1929. Serial No. 354,429.

My invention relates to a waterproof receptacle or carrying case, and the invention herein set forth is an improvement upon a somewhat similar waterproof receptacle forming the subject matter of my U. S. Letters Patent No. 1,671,385 issued to me May 29, 1928.

The principal objects of my present invention are to generally improve upon and simplify the construction of the waterproof receptacle disclosed in my aforesaid patent, and to provide improved means for effectually clamping and closing the mouth of the receptacle, which clamping and closing means is carried upon the container, thereby eliminating the possibility of the clamping means becoming lost or mislaid when the receptacle is opened.

A further object of my invention is to provide a waterproof receptacle or carrying case that is especially designed for bathers' use, although the container in larger sizes may be advantageously employed by hunters, fishermen, soldiers, campers or persons engaged in out-door sports or functions.

With the foregoing and other objects in view, my invention consists in certain novel features of construction and arrangement of parts that will be hereinafter more fully described and claimed and illustrated in the accompanying drawings, in which

Fig. 1 is a perspective view of a waterproof receptacle constructed in accordance with my invention and looking at the front side thereof.

Fig. 2 is a perspective view of the receptacle and looking against the rear side thereof.

Fig. 3 is a top plan view of the receptacle and showing the mouth-clamping means in closed position.

Fig. 4 is an elevational view of the upper end of the container with the clamping means in position thereon.

Fig. 5 is a horizontal section taken on the line 5—5 of Fig. 4.

Fig. 6 is a vertical section taken on the line 6—6 of Fig. 1.

Fig. 7 is a top plan view partly in horizontal section of the mouth portion of the

receptacle and showing a modified arrangement of the clamping means that is utilized for closing said mouth.

Referring by numerals to the accompanying drawings which illustrate a practical embodiment of my invention, 10 designates a substantially rectangular bag or container that forms the body of the receptacle, said body being preferably formed of rubber composition, and the upper end of said body terminates in a tapered neck portion 11, and extending upwardly from said neck portion is a pair of short vertically disposed walls 12 that normally lie parallel with each other, as illustrated in Figs. 3 and 5.

The opening between the walls 12 serve as the mouth of the receptacle and as the walls are formed of rubber or elastic material they may be readily spread apart and stretched to a certain degree to permit the insertion or removal of the contents of the receptacle.

Arranged on the outer faces of the walls 12 are short vertically disposed loops or keepers 13, the same being formed integral with said walls and extending through said loops and lying flat against the outer faces of the walls 12 are clamping members 14, preferably flat metal bars, the ends of which project slightly beyond the ends of said walls 12. These clamping members 14 are pivotally connected to each other at one end by means of a link or loop 16 that is pivotally connected to one of said bars and which may be swung into position over the end of the other bar, as illustrated in Figs. 3 and 5, thereby exerting clamping pressure upon the walls 12 to tightly close the joint or opening between said walls.

In order to prevent the clamping members 14 from becoming readily detached from the loops 13, said bars may be provided on their outer faces with notches or recesses 17 that receive the loops 13. (See Fig. 5.)

Where the receptacle is formed of relatively soft, flexible material, the body portion 10 thereof may be reinforced or stiffened by means of a substantially rectangular member 18, preferably formed of thin light-weight metal, such as aluminum, or from thin sheet material such as celluloid or fiber, and the

open upper end of said reinforcing member terminating just below the neck portion 11.

Formed integral with the upper end of one of the side walls of the body 10 is a flap or covering member 19 which is adapted to overlie the upper end of the container when the same is made ready for use, and said flap member is formed integral with one end of an elastic strap 20 that is adapted to pass around the lower portion of the body 10 and the opposite end of said strap being formed integral with the upper portion of the side wall a short distance below the point where flap 19 is connected.

15 The length of the flap 19 and elastic strap 20 is such that they must be stretched to a certain degree in order to be passed around the body 10, and thus the flap will be stretched tightly over the top of the receptacle so as to fully cover the mouth thereof and the clamping members that close said mouth.

Formed integral with the upper portion of the wall of body 10 to which the flap 19 and strap 20 are connected is a horizontally disposed strap 21 that is adapted to receive a portion of the clothing of the user of the receptacle, for instance the shoulder strap of a bathing suit, a belt, or a suspender strap.

39 In the use of my improved receptacle the clamping members 14 are released so as to permit the walls 12 to be spread apart, as illustrated by dotted lines in Fig. 3, thereby permitting articles such as cigarettes, matches, money, keys or jewelry to be placed within the container after which the clamping members 14 are brought together and secured in clamping position by the loop 16.

46 The closed mouth of the receptacle is now forced downwardly into the upper portion of the body 10 of the receptacle so that the walls 12 and clamping members 14 occupy positions within the upper portion of the body 10, as illustrated in Fig. 6, and the flap 19 and strap 20 are now manipulated so as to pass around the body of said receptacle with the flap thereof overlying the closed mouth and the clamping members applied thereto. Thus the flap 19 provides a smooth finish for the upper end of the receptacle and affords additional protection for the closed mouth thereof and effectually prevents moisture and dust from entering that portion of the body that is occupied by the mouth clamping means.

53 The clamping members 14 firmly grip and clamp the interposed walls 12, thereby effectually preventing the ingress of moisture and dust and affording complete protection for the contents of the container.

60 The receptacle may be conveniently carried in the pocket or traveling bag, or it may be directly applied to some part of the clothing of the wearer by passing a strap or the 65 like through or beneath strap 21.

In Fig. 7, I have shown the clamping bars that are carried by the mouth of the receptacle as being provided at both ends with readily detachable means that will permit said clamping members to be spread apart or moved toward each other instead of being pivotally connected to each other at one end. This readily detachable means takes the form of a loop or link that is pivotally connected to one end of each clamping member, and which is adapted to engage over the corresponding end of the other clamping member when the two members are brought to clamp the mouth of the receptacle.

70 Thus it will be seen that I have provided a waterproof receptacle that is relatively simple in construction, inexpensive of manufacture, and very effective in performing its intended functions.

75 It will be understood that minor changes in the size, form and construction of the various parts of my improved waterproof receptacle may be made and substituted for those herein shown and described without departing from the spirit of the invention, the scope of which is set forth in the appended claims.

80 I claim as my invention:

85 1. A receptacle formed of flexible waterproof material provided at its upper end with an opening, loops formed on the outer faces of the walls of said receptacle adjacent to said opening, rigid clamping members extending through and carried by said loops, the outer faces of which clamping members are notched for the reception of said loops, 90 said clamping members being pivotally connected to each other at one end, and readily releasable means for detachably connecting the other ends of said clamping members.

95 2. A container of the class described, comprising a receptacle formed of moistureproof material, which receptacle is provided at its upper end with an opening, loops formed on the walls of said receptacle adjacent to said opening, clamping members extending 100 through said loops, the outer faces of which clamping members are notched to receive said loops, a link connecting said clamping members at one end and a link pivotally connected to the opposite end of one of said clamping members and adapted to engage in a notch in the end of the other clamping member.

105 In testimony whereof I affix my signature.

DANIEL H. STRAYER.
